(57) **CLAIM**

The ornamental design for an electric blanket controller, as
shown and described.

DESCRIPTION

FIG. 1 is a perspective view of an electric blanket controller
showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 a partial enlarged view of portion 9 in FIG. 1; and,

FIG. 10 a partial enlarged view of portion 10 in FIG. 2.

The broken lines in the figures illustrate portions that form
no part of the claimed design.
